The ornamental design for a cable clamping insert, as shown and described.

DESCRIPTION

FIG. 1 is a front perspective view of the cable clamping insert according to the present disclosure;

FIG. 2 is a rear perspective view of the cable clamping insert of FIG. 1;

FIG. 3 is a front view of the cable clamping insert of FIG. 1;

FIG. 4 is a rear view of the cable clamping insert of FIG. 1;

FIG. 5 is a top view of the cable clamping insert of FIG. 1;

FIG. 6 is a bottom view of the cable clamping insert of FIG. 1;

FIG. 7 is a first side view of the cable clamping insert of FIG. 1; and,

FIG. 8 is a second, opposite side view of the cable clamping insert of FIG. 1.

The broken lines in the drawings illustrating structure that form no part of the claimed design.
